APPARATUS FOR ANNEALING ARTICLES

Carl O. Haase, Baltimore, Md., assignor to Western Electric Company, Incorporated, New York, N. Y., a corporation of New York

Application November 26, 1942, Serial No. 467,065

7 Claims. (Cl. 266—4)

This invention relates to apparatus for annealing articles, and more particularly to a regenerative water heating system for annealing furnaces.

Water seals are frequently used for preventing the entrance of air into annealing furnaces, since such seals are cheap and effective. Due to the difference in temperature of the tap water generally employed in water seals and the annealing gas in the heating chamber of the furnace, a considerable amount of heat is absorbed by the water in the water seal. When the heated water from the seal is withdrawn through an overflow pipe, the heat absorbed by the water is lost.

An object of this invention is to provide apparatus for annealing articles and more particularly to provide a regenerative water heating system for annealing furnaces.

In general, the invention comprises an annealing furnace having a water seal for sealing the furnace from the atmosphere, and means for spraying water from the water seal upon hot articles in the furnace to cool them, said means being so located that the water flows from the hot articles into the water seal.

Other features and advantages of the invention will become apparent from the following detailed description thereof, when read in conjunction with the accompanying drawing in which the single figure represents a schematic sectional view of an annealing furnace.

In the particular embodiment of the invention disclosed in the accompanying drawing, an annealing furnace is provided with a housing 10 which encloses a chamber 11 divided by a baffle 12 into a heating area 14 and a cooling area 15. An endless conveyor 17 located within the housing 10 comprises a motor driven sprocket 16 which is rotated at a constant speed and which, in turn, drives a chain 18 and a wheel 19. The wheel 19 acts merely as a tensioning wheel for the chain 18 and is located in a pit 20 which is normally filled with water, thus providing a water seal to prevent the entrance of air into the chamber 11. A plurality of spool carriers 21—21 are equally spaced upon the chain 18 for carrying through the chamber 11 coils of oxidizable metal wire weighing as much as 600 pounds wound on spools 22—22. A drum 23 formed on the sprocket 16 holds the spools 22—22 in position on the spool carriers 21—21 while they are passing over the sprocket 16.

A charging trench 24 provided with a cover 25 is formed in one side of the pit 20 and is filled with water from the pit 20. The spools 22—22 are fed down the charging trench 24 into the pit 20

10 and upon the conveyor 17 by means of an intermittently moving conveyor 26 which comprises a pair of sprockets 27 and 28 connected by a chain 29. A number of cross bars 30—30 are spaced along the chain 29 so as to permit spools 22—22 to be positioned therebetween. When a spool 22 is fed from the conveyor 26 into the pit 20 and onto the conveyor 17, stops 31, 32 and 33 position the spools 22—22 so that they are engaged by the spool carriers 21—21.

The spools 22—22 are moved upwardly through the heating area 14 in which electrical heating means 37 are located. The particular type of heating means employed does not constitute part 15 of this invention, but one type of heating means that has proved satisfactory comprises a plurality of heating coils arranged in a grid-like formation and disposed so as to form three heating areas. In the cooling area 15 opposite the heating area 14 are positioned a plurality of spray nozzles 34—34 which are supplied with water pumped from the body of water forming the seal in the pit 20 by a pump 35. The pump 35 is an impeller type pump having an inlet pipe 36 extending below the surface of the water in the pit 20, and pumps the water up through a pipe 38 to branch pipes 39—39 which feed the nozzles 34—34. A trip 40 is so disposed relative to the path of movement of the spools 22 through the heating chamber 11 that it rolls the spools from the spool carriers 21—21 through an opening 43 in the housing 10 onto a discharge apron 41 and into a discharge drum 42. A rotating discharge valve 44 positioned within the drum 42 has two recesses 45—45 formed therein for receiving the spools 22—22. A pocket 46 is formed in each recess 45 for the purpose of carrying a spool deposited therein to a rack 48. The recesses 45—45 in the rotating member 44 are so formed that the opening 43 is always closed and the heating chamber 11 thus is sealed from the atmosphere.

In operating a furnace such as that shown in the accompanying drawing, spools 22—22 carrying coils of wire made of an oxidizable metal, such as copper, are introduced into the charging trench 24, and are inserted in the conveyor 26 one at a time. The water in the water seal is initially heated by passing steam into it, so that 45 as the conveyor 26 moves the spools 22—22 slowly down the charging trench 24, the coils of wire carried by the spools become heated through to about the temperature of the water in the water seal, which is about 190° F. to about 200° F., and the occluded gases in the wire coils expand due

to the heat and are forced from the coils by the water. The intermittent movement of the conveyor 26 is timed so that a spool from the conveyor 26 rolls freely down the charging trench 24 toward the stops 31, 32 and 33 whenever a spool carrier 21 on the constantly moving conveyor 17 reaches the bottom of the trench 24 and is positioned by the stops in a spool carrier.

The conveyor 17 moves the spools 22-22 upwardly through the heating area 14 in which the heating means is located at a rate of movement such that the wire carried by the spools 22-22 becomes thoroughly heated to the proper temperature by the time it reaches the sprocket 16. Since the wire coils on the spools are preheated nearly to the boiling point of water before entering the heating area 14, the spools may be moved up past the heating means much faster than if the wire were not preheated and were wetted by relatively cold water having a temperature of about 40° F. to about 70° F. The drum 23 formed on the sprocket 16 supports the heated spools 22-22 as they pass over the top thereof into the cooling area 15. The conveyor 17 moves the spools carrying the coiled wire downwardly through the cooling area 15 advancing the spools 22-22 past the cooling nozzles 34-34 located therein which are supplied with heated water from the pit 20 by the pump 35 through the pipes 36, 38 and 39-39. When the water from the nozzles 34-34 is sprayed upon the hot coils of wire carried on the spools 22-22, all of the heat in the coiled wire is utilized either for evaporating the cooling water sprayed thereon into steam or for heating the water sprayed thereon so that as this water flows back into the water seal, it heats the water contained therein.

The generation of steam in this manner has two beneficial effects: First, the steam provides a non-oxidizing atmosphere within the chamber 11 which prevents oxidation of the wire that is being treated. Second, it permits the maintenance of a slight steam pressure within the chamber 11 which is desirable since it prevents any air from entering therein. The heat absorbed by the water in the water seal is utilized to preheat the wire on the spools as they are advanced down the charging trench 24, and is further useful in promoting rapid evaporation of the water ejected from the nozzles 34-34. Since ordinarily tap water has a temperature of approximately 40° F. to 70° F., when it is sprayed onto the hot coils of wire it is so cool that it cools the coils of wire or portions thereof below the boiling point of water and thus permits the cold water to flow into the convolutions of the coils, so that the coils of wire are wet when ejected from the furnace. Conversely, when the heated water from the water seal is sprayed onto the hot coils of wire, this water is so near its boiling point that it cannot cool the coils of wire below this temperature and, consequently, no water can remain upon the wire which is ejected, cooled and dried from the furnace.

The water that flows from the spools 22-22, the water that does not strike the spools 22-22, and the water that is formed by the condensation of steam on the side walls of the chamber 11 is collected in the pit 20. Enough heat is absorbed by the water that runs off after striking the hot spools 22-22 to maintain the temperature of the water in the pit 20 between about 190° F. and about 200° F., so that after the furnace has been operating for a short time, the pit water need no

longer be heated by steam introduced therein. In order to prevent the water in the pit 20 from rising above 200° F., which would cause excessive generation of steam, it is advisable to provide a small flow of cold water into the pit 20, which also maintains the water level constant and compensates for water lost due to evaporation.

The spools 22-22 pass downwardly past the nozzles 34-34 until they strike the trip 40 which is positioned so as to roll the spools 22-22 one at a time from the spool carriers 21-21 onto the apron 41 and through the opening 43 into the discharge drum 42. The rotatable discharge valve 44 is operated intermittently and in synchronism with the conveyor 17 so as to present a recess 45 to the opening 43 simultaneously with the rolling of a spool onto the apron 41 by the trip 40. Each spool 22 is carried in the pocket 46 to a point where it is discharged from the discharge drum 42 onto the rack 48, the construction of the drum 42 being such that it does not allow air to enter the cooling area 15 when a spool is discharged therefrom.

The time required for the entire operation from the time a spool enters the charging trench 24 until it is ejected from the drum 42 is greatly reduced by the use of the regenerative water heating system disclosed in the accompanying drawing. There are several reasons why this remarkable reduction in the time required for the annealing operation is thus effected. In the first place, wire passed through a water seal containing cold water is cold when introduced into the heating area and both the cold wire, weighing up to 600 pounds, and the cold water clinging thereto must be gradually heated. The hot water in the water seal, forming part of the above described regenerative water heating system, preheats the wire coiled upon the spools 22-22 to about 200° F., and when the preheated coils of wire are carried by the conveyor 17 into the heating area 14, the hot water still clinging to the wire is quickly heated to the boiling point and evaporated, thus leaving the wire completely dry. Since the wire coils are preheated to about 200° F. before they enter the heating area 14, and because the hot water that remains on the wire is already at a temperature near its boiling point, considerably less time is required to heat the wire to the proper temperature for annealing than is the case where the water in the water seal is cold and 400 to 600 pounds of wire and the water clinging thereto must be heated beginning at a temperature as low as 40° F.

Furthermore, when cold water is employed in the water seal and is constantly siphoned off in large quantities, the heat absorbed by the water is continually being drained from the furnace. The heat thus lost is considerable because the water absorbs a large amount of heat due to the high temperature of the annealing atmosphere within the heating area 14 maintained by the electric heating elements 31. The regenerative water heating system hereinabove described materially reduces this loss of heat and, as a result, increases the thermal efficiency of the furnace to such an extent that it is practically self-sufficient after it has been in operation for a short period of time, and very little, if any, steam from an outside source is required.

What is claimed is:

1. In an annealing furnace, a regenerative water heating system comprising a water seal, means for spraying water onto articles heated

in the furnace, and means for supplying the spraying means with water from the water seal, the spraying means being so located that water from the articles flows into the water seal.

2. In an annealing furnace, a water seal forming the bottom of the heating chamber in the furnace to prevent entrance of air into the chamber, a plurality of spaced nozzles for directing sprays of water onto hot articles to cool them, the excess water flowing from the articles down into the water seal, and means for supplying the spraying means with water from the water seal.

3. In an annealing furnace having an endless conveyor for carrying articles to be annealed, a water seal for preventing the entrance of air into the furnace, means for heating the water in the seal, and means for spraying heated water from the water seal upon the articles carried by the conveyor, said water seal being so located as to collect therein all of the water within the furnace.

4. In an annealing furnace including a heating chamber, an endless conveyor within the heating chamber, means for feeding articles to be annealed to the conveyor, and means for heating the articles carried by the endless conveyor, a water seal for preventing air from entering the furnace, means for spraying water onto the hot articles, means for supplying water from the water seal to the spraying means, and means for ejecting the articles from the heating chamber.

5. In an annealing furnace having a constantly driven endless conveyor for carrying spools wound with wire made of oxidizable metal in a path through the furnace, a second endless conveyor intermittently operated having its movement synchronized with that of the constantly driven conveyor to permit the feeding of the spools from the intermittently operated conveyor to the constantly moving conveyor, electrical means for heating the spools disposed about a

portion of the path of the spools through the furnace, a plurality of spraying nozzles disposed about a portion of the path of the spools through the furnace which is opposite the heating means,

5 a water seal for sealing the interior of the furnace from the atmosphere, means for heating the water in the water seal, and means for supplying water from the water seal to the spraying means, the water flowing from the spools to the

10 water seal.

6. In an annealing furnace including a chamber, a water seal at the bottom of the chamber for preventing the entrance of air into the chamber, means for introducing articles to be annealed 15 into the water seal to preheat them, means for conveying the preheated articles from the water seal and through the chamber, means for heating the articles carried by the conveying means, and means for spraying water from the water seal upon the heated articles carried by the conveying means, the water seal being so located 20 that all the water flowing downwardly in the chamber collects in the seal and supplies heat to the water in the seal.

7. In an annealing furnace, a chamber comprising a heating zone and a cooling zone, a water seal at the bottom of the chamber in communication with both the heating and cooling zones, means for maintaining the water in the seal at a 25 predetermined elevated temperature, means for introducing articles to be annealed into the water seal to preheat them, means for conveying the preheated articles from the water seal through the heating and cooling zones, means in the cooling zone for spraying water upon the heated articles carried therethrough, and means for supplying water from the water seal to the spraying means, the water seal being so positioned that 30 water flowing downwardly in the chamber collects in the seal and supplies heat to the water in the seal.
